[57] CLAIM

The ornamental design for a sink, as shown and described.

DESCRIPTION

FIG. 1 is a top perspective view of a sink showing our new design;

FIG. 2 is a top plan view thereof;

FIG. 3 is a sectional view along line 3—3 of FIG. 2;

FIG. 4 is a sectional view along line 4—4 of FIG. 2;

FIG. 5 is a sectional view along line 5—5 of FIG. 2; FIG. 6 is a top plan view of a modified form of the sink shown in FIG. 1; and

FIG. 7 is a section view along line 7—7 of FIG. 6.

The fragmentary broken line representations of counter tops in FIGS. 1 and 6, and of fitting holes in FIGS. 1 and 2 are for purposes of illustration only.
